PROCESS FOR THE TREATMENT OF
COMPOSITION AND CEMENTITIOUS
MATERIALS

David H. Levine, New Haven, Conn.

Application August 25, 1934, Serial No. 741,397

8 Claims. (Cl. 25—154)

My invention relates to processes for treating composition and cementitious materials and refers particularly to steps in the process of treating such deposits suitable for roads, walks, foundations and similar purposes.

My process is particularly advantageous in the building of composition and cementitious materials for road purposes and I will refer specifically to such production, but not limiting my invention thereto.

In the building of a composition concrete road, the concrete is laid down upon and spread over a suitable foundation material in a wet condition and it must be allowed to age, or dry, under such conditions as will cause an effective binding between the materials of the composition.

Experience has shown that if the concrete is allowed to dry too rapidly, the surface is dried before the interior of the mass, resulting in an uneven binding of the materials of the composition thus producing an uneven, and ineffective material for traffic purposes which is liable to crack and disintegrate.

It is, therefore, necessary to control the rapidity of the evaporation of the water in the concrete mass in such a manner that it will occur upwardly from the interior of the mass, the surface being the last to harden.

The usual practice followed to accomplish this desired result is to cover the surface of the newly laid concrete with burlap, hay or straw and to pour water over this covering from time to time, thus keeping the concrete face in a moistened condition and allowing of the upward evaporation of the water in the mass.

As the covering materials now employed are non-absorbent or only slightly absorbent of water, the greater portion of the applied water runs through the covering and away from the concrete surface and is hence ineffective for the desired result.

In practice it has been found that this covering must have water poured, or sprinkled, upon it every two or three hours for a period of about seven days, and as water is frequently difficult to obtain along the roadway, this process is expensive and is uneconomic as to both time and expense.

My invention overcomes the above mentioned, and other, objectionable features of the present employed methods and presents means whereby more effective and uniform results can be obtained with less water and in a greatly reduced period of time.

I have found that if the surface of the freshly

laid concrete be covered with a water-saturated web of loosely matted water-absorbent material, the evaporation of the water of the concrete mass will take place evenly over its entire surfaces, and hence evenly throughout the mass, and that a satisfactory result can usually be obtained within a period of seventy-two hours.

I have further found that usually the water contained in the saturated web is sufficient to accomplish the desired result, although additional water may be applied if required.

As my device is in the form of a web, or pad, it can be readily and quickly laid upon the surface of the concrete, it overcomes the difficulty incident to the spreading of hay and straw, and as it can be as easily removed as a unit construction, there are no loose materials requiring collection and removal.

Further as my device can be employed for repeated operations it presents a very considerable saving in money investment.

My invention consists in the employment of a web, or pad, of loosely matted fibrous water-absorbent material, such as cotton, of sufficient strength to permit considerable or sustained handling, and if necessary, it may be covered by attached layers of an easily water permeable fabric which will allow of the unimpeded evaporation of water therethrough.

I prefer that these outer layers be of net-like construction of jute, cotton, wool or other suitable threads.

My web may be of any width and length, but it is of course advisable to make it of the size of the standard road dimensions.

In following the process of my invention, I prefer to pass my web, or pad, through a trough of water so as to thoroughly soak it and then spread it upon the freshly laid concrete and experience has shown that the amount of water thus absorbed is usually sufficient for the proper evaporation of the water in the concrete mass and that further water need not be applied.

The dry web or pad, may be spread upon the concrete mass and water sprinkled thereover, but the same uniformity of water absorption can not be thus obtained as is possible by the first described method.

When the water has evaporated from my device and the concrete mass, my device is rolled, preferably on a wooden rod, passed through a trough of water and spread upon a new surface of concrete.

In the accompanying drawing illustrating one

form of a device suitable for my process, similar parts are designated by similar numerals.

Figure 1 is a top plan view of one form of a device adapted to the process of my invention.

Figure 2 is a section through the line 2-2 of Figure 1.

Figure 3 is a top plan view of the device placed upon a concrete-cement deposit, broken away for clearness of description.

10 The device shown in the accompanying drawing as suitable for application in my process consists of a sheet, web, or pad, of loosely matted cotton 10, which is enclosed in an upper and lower net-like material formed by the jute threads 11-11. The jute nettings are attached to each other and to the cotton pad by means of stitching 14-14.

15 In Figure 3 showing the application of the device of Figures 1 and 2, the deposit mass consists of a concrete bed 12, covered by a cement layer 13. The web device 10, 11 is spread upon the freshly laid concrete cement deposit as shown and the combination allowed to dry by evaporation, or the dry device is spread upon the deposit and then 20 moistened and allowed to dry by evaporation.

25 Among the other advantages possessed by the following of my process are the protection of the deposit from the influence of the sun and weather, the prevention of the deposit from sudden changes of temperature, and the gradual cooling of the deposit through the matted material.

30 Experiments have shown that because of the properties of the materials employed in my process, and particularly because of the uniform moisture content of the deposit during curing, the 35 flexual strength of the finished product is very considerably increased.

35 By composition and cementitious materials I mean deposits of compositions and mixtures of cementitious materials which when deposited in a wet condition and allowed to dry will produce hard substances adapted for traffic and other uses.

40 It will thus be seen that in my process I employ an inexpensive device, capable of re-use, for the 45 production of improved and more uniform results at a considerable saving of time and expense over the present employed methods.

45 I do not limit myself to the particular products and steps of procedure specifically mentioned, as 50 these are given simply as a means for clearly describing my invention.

55 What I claim is:—

1. A process for treating cementitious materials which comprises spreading a pad of loosely

matted cotton covered on both sides by a loosely woven netting over a mass of freshly laid wet composition or cementitious materials and applying water to said pad and allowing the water to evaporate from said deposit and said pad. 5

2. A process for treating cementitious materials which comprises spreading a pad of loosely matted cotton attached by stitches to and covered on both sides by a loosely woven netting over a mass of freshly laid wet compositions or cementitious materials and applying water to said pad and allowing the water to evaporate from said deposit and said pad. 10

3. A process for treating a concrete deposit which comprises spreading a pad of loosely matted cotton covered on both sides by a loosely woven netting over a mass of freshly laid wet concrete deposit and applying water to said pad and allowing the water to evaporate from said deposit and said pad. 15

4. A process for treating a concrete deposit which comprises spreading a pad of loosely matted cotton attached by stitches to and covered on both sides by a loosely woven netting over a mass of freshly laid wet concrete deposit and applying water to said pad and allowing the water to evaporate from said deposit and said pad. 20

5. A process for treating cement and cementitious materials which comprises spreading a wet pad of loosely matted cotton covered on both sides by a loosely woven netting over a mass of freshly laid wet composition or cementitious material and allowing the water to evaporate from said deposit and said pad. 25

6. A process for treating cement and cementitious materials which comprises spreading a wet pad of loosely matted cotton attached by stitches to and covered on both sides by a loosely woven netting over a mass of freshly laid wet composition or cementitious material and allowing the water to evaporate from said deposit and said pad. 30

7. A process for treating a concrete deposit which comprises spreading a wet pad of loosely matted cotton covered on both sides by a loosely woven netting over a mass of freshly laid wet concrete and allowing the water to evaporate from said deposit and said pad. 35

8. A process for treating a concrete deposit which comprises spreading a wet pad of loosely matted cotton attached by stitching to and covered on both sides by a loosely woven netting over a mass of freshly laid wet concrete and allowing the water to evaporate from said deposit and said pad. 40
